UNITED STATES PATENT OFFICE.

JOHN M. BLAND, OF KANSAS CITY, MISSOURI.

WAGON-BED LIFTER.

SPECIFICATION forming part of Letters Patent No. 244,732, dated July 26, 1881.

Application filed December 14, 1880. (No model.)

To all whom it may concern:

Be it known that I, JOHN M. BLAND, of Kansas City, in the county of Jackson and State of Missouri, have invented certain new and useful Improvements in Wagon-Bed Lifters; and I do hereby declare that the following is a full, clear, and exact description of the invention, which will enable others skilled in the art to which it appertains to make and use the same, reference being had to the accompanying drawings, which form a part of this specification.

Figure 1 is a view, in perspective, of a wagon-bed lifter embodying my improvements; and Fig. 2 is a side elevation, showing the crane-arm folded down for transportation.

This invention has relation to portable cranes for lifting wagon-beds and the like in form or other use; and it consists of the improved features of construction and combination herein-after fully described, and particularly pointed out in the claims.

Referring by letter to the accompanying drawings, the base of the machine consists of two pieces, A and B, intersecting each other at right angles, the top piece being recessed at its middle to embrace the bottom piece, and provided at its ends with blocks *a a* to level the base and make it set evenly upon the ground. The ends of the cross-pieces A and B are provided with holes *b b*, through which stakes are to be driven to secure the machine firmly to the ground. From the bottom piece, A, rises a post, C, to the rear face of which the windlass D is secured in any suitable manner. An upright, E, is stepped in the piece A, immediately in front of the post C, and is secured to the latter by staples F, so that the upright may be turned completely around, if desired, or swung to either side from a normal position.

At a point a short distance above the top of the post C the crane-arm G is hinged to the upright E, and a cap-brace, H, extends from the top of the upright, to which it is connected by a mortise and tenon, to the crane-arm G, to which it is also connected by a mortise and tenon, as shown. A bolt-rod passes through

the crane-arm G and through the cap-brace H, which, when the crane-arm is to be folded down to permit the machine to be transported, is to have the nuts *c* removed, and the rod may then be withdrawn for this purpose. The cap-brace is provided at its rear end with a pulley, J, and the crane-arm is provided at its front end with a pulley, K. A rope, L, connected with the windlass runs over these pulleys, and double rings M are secured to the free end of the rope. From these rings M four ropes, N, provided with hooks O, depend, and they are especially intended to be connected with a wagon-bed to raise it when the windlass is operated, and permit it to be swung over the wagon-gear and placed thereon, and this operation can be performed by a single man unaided, as the windlass is provided with the usual pawl and ratchet, and the weight may be stopped at any point of the elevation or descent.

It is evident that the device may be used for analogous purposes.

The folding crane-arm is the essential feature of the invention, as this renders the device portable. It is cheap, simple, and durable, and may be used by a single person unaided by others.

Having thus fully described my invention, what I claim as new, and desire to secure by Letters Patent, is—

1. In a wagon-bed lifter, the combination of the base A B, the post C, and windlass D, with the upright E, having crane-arm G and cap-brace H, and a removable bolt-rod connecting the cap-brace and crane-arm, substantially as set forth.

2. In a wagon-bed lifter, the upright E, having hinged crane-arm G, in combination with the cap-brace H, adjustably secured to the arm G by a bolt, or its equivalent, substantially as and for the purpose shown and specified.

In testimony that I claim the foregoing as my own I have hereto affixed my signature in presence of two witnesses.

JOHN MILES BLAND.
